UNITED STATES PATENT OFFICE.

COME DESHAIES, OF CENTRAL FALLS, RHODE ISLAND.

TWISTING FRAME.

Application filed February 21, 1922. Serial No. 538,315.

To all whom it may concern:

Be it known that I, COME DESHAIES, a citizen of the United States, residing at Central Falls, in the county of Providence and 5 State of Rhode Island, have invented certain new and useful Improvements in Twisting Frames, of which the following is a specification.

This invention relates to an improved 10 thread-severing attachment for twisting-frames, and has for its object to provide means whereby when the thread on the delivery side of the draft rolls is broken this attachment will act to sever the thread on 15 the supply side of said rolls to prevent further drawing of the thread from the supply spools by said rolls and the device also serves to clamp the severed end of the thread to prevent it from being engaged and drawn 20 out by adjacent running threads.

With these and other objects in view, the invention consists of certain novel features of construction, as will be more fully described, and particularly pointed out in the 25 appended claims.

In the accompanying drawings:

Figure 1 is a side elevation partly in section showing the tension-lever as engaging and feeling of the running thread as it is 30 drawn from the supply-spool and wound upon the bobbin, also showing the severing and damping mechanism held in inoperative position by the tension-device.

Figure 2 is a front elevation of the up- 35 right cutting and clamping spindle supported in raised position and showing the thread-receiving slot, the clamping ring and the cooperating thread-shearing bearing member also showing the mouth of the 40 thread-entering slot as covered by the clamping ring.

Figure 3 is a side elevation of the spindle shown in Figure 2 and showing the tension feeler cam as supporting the spindle in 45 raised or inoperative position.

Figure 4 is the same as Figure 3 but showing the cam as removed from beneath the spindle and the latter as being dropped to sever the thread and bind the severed 50 end.

Figure 5 is a detail showing a hook member for retaining the tension feeler and severing member in inoperative position while the broken thread is being re-threaded 55 into the machine.

It is found in practice very desirable particularly in thread-twisting frames and the like, where the thread is drawn from a supply spool to be moistened and wound upon a bobbin, to provide means for feeling of the 60 thread and applying sufficient tension thereto to break the thread if it is not of the required strength and if said thread is broken to provide means for immediately severing the thread on the opposite side of 65 the draft rolls to prevent more thread from being drawn from the spool by the rolls until the broken ends are tied together. It is also found to be of advantage to clamp and bind the severed end of this thread to 70 prevent it from engaging adjacent threads or being wound and accumulated upon the draft-rolls or other moving portion of the machine; and the following is a detailed description of one means by which this result 75 may be accomplished:—

In thread-twisting machines of this character the thread is drawn from a supply spool 10 down through a moistening tank 11, up through the guide eye 12 over the 80 draft-rolls 13 and 14 and wound upon a driven bobbin 15, and it is found to be of advantage to provide means for testing the strength of the thread during its running from the supply spool to the bobbin and if 85 it is found to be too weak, to break the same at a point between the rolls and the bobbin to be subsequently pieced up, and at the same time to clamp the thread on the opposite side of the rolls to prevent more 90 thread from being drawn from the spool after the break occurs.

I have provided an improved means for accomplishing this purpose which will not only sever the thread on the supply side 95 of the rolls but also clamp this severed end to prevent it from being wound or accumulated about the rolls or from becoming twisted and snarled with adjacent running threads, which mechanism comprises essentially a bearing member 16 clamped to the frame portion 17 of the machine in which bearing is adjustably mounted, by a set screw 18, a sleeve 19 at the lower end of which is pivoted at 20 the tension feeler 100 lever 21, the engaging end of this feeler-lever being provided with an endwise adjustable feeler member 22 which is clamped at 23 to the arm 21 to be set to properly engage the running thread. 105 110

This feeler lever is provided with a rearwardly-extending arm 24 on the opposite side of the pivot 20, which arm is adapted to carry a plurality of weights 25, which may be varied in number and position to apply the proper tension to threads of different sizes to cause them to break if not of required strength.

- 10 This lever is provided with a cam-shaped arm 26 extending into the slot 27 of the sleeve 19, which arm is provided with a stop finger 28 resting against the outer surface of the sleeve to support the lever in proper working position. In this sleeve I have mounted a vertically-movable spindle 29 provided with a weight 30 at its upper end and arranged at its lower end 31 to rest upon and be supported by the upper face of the cam arm 26.
- 15 20 This spindle is provided with a vertical slot 32 through which the thread 33 passes in running from the guide eye 12 over the draft roll 13.

- 25 Communicating with this vertical slot is a laterally and downwardly extending entering slot 34 through which the bight of the thread is passed into the main slot 32 by raising the spindle to lift the mouth of the slot above the ring presently described.
- 30 35 In order to lock this spindle in its sleeve 19, I have inserted a pin 35 into the spindle and have provided a zigzag-shaped entering groove 36 in the upper end of the sleeve 19 which communicates with the straight slot 36 therein, which vertical slot serves as a guide for the operating movement of the thread-severing spindle 29.

- The edge portion 37 of the slot 32 in this spindle is very sharp and when cooperating 40 with the similar edge portion of the sleeve 19 serves to sever the thread as the weighted spindle drops upon being released by its supporting cam 26, thereby preventing more thread from being drawn from the spool by 45 the draft rolls 13 and 14 when the thread is broken by the tension feeler 21. I have also provided about this spindle a collar member 39 which has an internal diameter of sufficient size to just permit the thread 50 to be drawn down therebetween and jam or clamp the thread by the quick downward severing motion of the weight-spindle thereby preventing the free end of the thread 55 from getting tangled with the adjacent running threads.

- Similar collars 39 with different sized holes therein may be employed to receive threads of different sizes which may be run through the machine.
- 60 By this construction above described it will be seen that when the thread is broken by the tension feeler at a point between the draft-rolls and the bobbin, the weighted end of the lever which has been retained in 65 raised position by the tension of the thread

on its opposite end now immediately drops and withdraws the cam-arm 26 from beneath the end 31 of the spindle 29 which under the action of its heavy weight 30 immediately drops causing its sharp edge 37 to 70 cooperate with the sharp edge 38 of the sleeve 19 to sever the thread on the supply side of the draft rolls and prevent further drawing of the thread by said rolls from the spools also the dropping of the spindle 75 carries the bight of the thread down through the large collar 39 clamping it therein to prevent its end from engaging the adjacent threads or other running parts of the machine.

80 After the thread has been broken and during the piecing up operation it is found to be desirable to lift and hold the thread-severing spindle 29 in its raised position. To accomplish this in a simple and effective 85 way, I have provided a detent 40 which is pivoted at 41 and provided with a hook end 42 to be swung around and engage the lever 21 when in operative position thereby retaining this lever and the spindle 29 in 90 this operative position during the time that the broken thread is being re-threaded and its ends knotted, after which this detent may be swung back to release the lever to function.

95 The foregoing description is directed solely towards the construction illustrated, but I desire it to be understood that I reserve the privilege of resorting to all the mechanical changes to which the device is susceptible, the invention being defined and limited only by the terms of the appended claims.

I claim:

1. In a twisting frame having draft rolls, a thread tensioning lever weighted at one end and engaged by the thread at the other end on the delivery side of said rolls to hold said lever in normal position, a weighted upright spindle having thread severing and clamping means located on the supply side of said rolls and a cam controlled by said lever for normally retaining said spindle in inoperative position whereby the breaking of said thread operates said lever and cam to release said spindle to function.
2. In a twisting frame having thread draft rolls, a tension lever with weights on one end pivotally mounted to engage the thread on the delivery side of said rolls, an upright weighted spindle, thread severing and clamping means controlled by said spindle and normally supported in inoperative position by said tension lever engaging said thread whereby the breaking of said thread on the delivery side of said rolls causes said severing and clamping means to function.
3. In a twisting frame having draft rolls, a tension lever with weights on one end and

mounted to engage the thread on the delivery side of said rolls, an upright spindle having a slot with a severing edge and through which the running thread is led, co-operating severing and clamping members in which said spindle is slidably mounted, said spindle being normally supported in inoperative position in said members by the tension of the thread upon said lever, where-by the breaking of said thread releases said lever to move under action of its weights and release said spindle to descend and function.

4. In a twisting frame having draft rolls, a weighted lever for tensioning the thread on the delivery side of said rolls, an upright weighted spindle having thread-severing and clamping means adapted to engage the thread on the supply side of said rolls, a cam on said lever normally supporting said spindle in inoperative position whereby the breaking of the thread releases said lever and cam to move under action of its weight to release said spindle to function.
5. In a twisting frame having draft rolls, a weighted lever for tensioning the thread on the delivery side of said rolls, an upright

weighted spindle having thread-severing and clamping means adapted to engage the thread on the supply side of said rolls, a cam on said lever normally supporting said spindle in inoperative position whereby the breaking of the thread releases said lever and cam to move under action of its weight to release said spindle to function, and means for retaining said lever and spindle in operative position during a re-threading operation.

6. In a twisting frame having draft rolls, a weighted lever for tensioning the thread on the delivery side of said rolls and having a cam-shaped supporting member, a vertically movable spindle normally supported in inoperative position by its lower end on said cam, said spindle having a severing edge beneath which the thread is drawn, a loose ring on said spindle and a cooperating severing edged bearing sleeve for said spindle, whereby the breaking of the thread releases said lever to withdraw said cam and permit the spindle to drop to sever the thread and bind its severed end in said ring.

In testimony whereof I affix my signature.
COME DESHAIES.
